UNITED STATES PATENT OFFICE.

CONRAD D'ANGELO, OF NEW YORK, N. Y.

ARMY-LEGGING.

1,254,462.

Specification of Letters Patent. Patented Jan. 22, 1918.

Application filed July 12, 1917. Serial No. 180,063.

To all whom it may concern:

Be it known that I, CONRAD D'ANGELO, a citizen of the Republic of France, now residing at the borough of Manhattan, city, 5 county, and State of New York, have invented an Improvement in Army-Leggings, of which the following is the specification.

Heretofore so far as I am aware army leggings as customarily made have been 10 manufactured of leather, canvas, duck, or similar materials, and made to fit or conform to the calf of the leg of the wearer, being secured in place by means of straps and buckles or lacing, or other similar devices. As will be apparent therefore, in 15 ordinary army leggings it was necessary in almost every instance to make the leggings to order or measure to have them fit properly, as naturally arises from the different 20 sizes and configurations of the calves of the legs of the wearers of the articles. The object of my present invention is to overcome this difficulty and to provide a legging which is made so as to be applied and to 25 fit the calf of the leg of any person irrespective of the size and shape of the same.

In carrying out my invention the improved form of legging is made from khaki or woolens or any approved army cloth and 30 cut into a strip, one end of which is adapted to fit the ankle of the wearer, while an intermediate or central portion is adapted to be wound around the calf of the leg of the wearer, and the opposite or top end is provided at its extremity with a tab adapted 35 to be tucked between the folds of the legging so as to secure the same in position.

The legging will be hereinafter more particularly described in conjunction with the 40 accompanying drawing in which:

Figure 1 is a plan view illustrating the configuration of the legging.

Fig. 2 is a rear elevation showing the application of the legging in use, and

Fig. 3 is a front elevation of the same.

Referring to the drawing the legging made in accordance with this invention preferably comprises a strip of material indicated at 10 and at one end, which for the 45 purpose of description will be called the lower end, the strip of material is curved in plan in one direction as indicated at 11 and at this end an end piece 12 is employed and adapted to continue the general conformation of the strip at this end thereof. The 50 extremity of the strip and the adjacent side

of the end piece are suitably connected along a line indicated at 13. This may be done by stitching or lacing or in any suitable manner and on both sides of this joint between the lower end of the strip proper and the end piece, the inner side of the strip of material is reinforced by a padding of leather or other similar material indicated at 14. This may be secured in position by lines of stitching 15 or otherwise. The purpose of employing this end piece is in order that depending upon the position in which the same is attached the lower end of the legging may be made to conform to 70 different sized and shaped ankles, taking also into consideration the height of the instep of the wearer.

At the opposite end the strip forming the legging is in plan curved in the opposite 75 direction as indicated at 16 while the intermediate portion of the strip as indicated at 17 is substantially straight. At the upper or curved end of the strip the extremity thereof is provided with a tab 18 preferably 80 extending at right angles thereto as plainly indicated in Fig. 1 of the drawing.

From the foregoing it will be apparent that in plan the legging made in accordance with my invention is substantially made 85 in an ogee curve with the lower end thereof curved in plan and in one direction, and the radius of the curve relatively small, while the upper end thereof is curved in plan in the opposite direction with the radius of the curve relatively large, and the central portion thereof is substantially straight.

In the application of this legging the lower end thereof is placed around the ankle 95 as indicated in Fig. 2 with the reinforcing pad innermost and in the position as shown in this figure. The legging is then wound around the calf of the leg and is of length sufficient to reach when so wrapped, to a 100 point appreciably below the knee. After being so wrapped the tab 18 at the upper end of the legging is tucked up between adjacent folds thereof so as to secure the legging in position on the wearer.

I claim as my invention:

1. As a new article of manufacture, a legging comprising a strip of material having at its lower end a curved portion the center of which is adapted to lie at the back 110 of the ankle with the lower extremity extending over the front of the ankle, a rela-

tively straight central portion adapted to be wound around the calf of the leg of the wearer, and an upper curved portion with an extension at an angle thereto at its extremity adapted to be tucked under the top fold of the legging.

2. As a new article of manufacture, a legging comprising a strip of cloth having a curved lower end adapted at its extremity to lie at the back of the ankle of the wearer, an end piece secured to the lower end of the

legging and continuing the curve thereof and adapted to extend over the front of the ankle of the wearer, a relatively straight central portion adapted to be wound around the calf of the leg of the wearer, and a curved upper portion with a tab at right angles at the extremity thereof, the said tab being adapted to be tucked up under the top fold of the legging.

Signed by me this 7th day of July, 1917.

CONRAD D'ANGELO.
